UNITED STATES PATENT OFFICE.

WINGO HERRON AND JOSEPH H. JESTER, OF AUGUSTA, GEORGIA.

SPLIT HUB HEAD FOR CYLINDERS FOR SPINNING FRAMES, SPOOLERS, AND CYLINDERS OF LIKE NATURE.

Application filed March 7, 1922. Serial No. 541,654.

To all whom it may concern:

Be it known that we, WINGO HERRON and JOSEPH H. JESTER, citizens of the United States, and residents of the city of Augusta, 5 county of Richmond, and State of Georgia, have invented certain new and Improved Split Hub Heads for Cylinders for Spinning Frames, Spoolers, and Cylinders of like Nature, of which the following is a 10 full, clear, and exact description.

Our invention relates to improvements in spinning frame cylinders, and it consists in the combinations, structures and arrangements herein described and claimed.

15 An object of our invention is to provide a spinning frame cylinder which is constructed in such manner as to permit of the disassembly of the cylinder and the removal or replacement of a shaft upon which 20 the cylinder is mounted with the necessity of removing the cylinder from the cylinder frame obviated.

25 A further object of our invention is to provide in a cylinder of the character described a novel cylinder head.

Other objects and advantages will be apparent from the following description, and the novel features of the invention will be particularly outlined in the appended claims.

30 Our invention is illustrated in the accompanying drawings, forming a part of this application, in which:

Figure 1 is a fragmentary view mainly in side elevation and partly in section of a 35 cylinder head embodying our invention operatively applied,

Figure 2 is an enlarged side elevation of the cylinder heads shown in Figure 1, and

40 Figure 3 is an end view of the cylinder head.

Referring now to the drawings, the numeral 1 designates a shaft on a spinning frame, not shown. The shaft 1 carries the 45 spinning cylinder in which an embodiment of our invention is comprised and is in general of conventional construction, differing therefrom only in the particulars which will be hereinafter specifically set forth.

50 In carrying out our invention, a head 2 having a hub 3 provided with a bore of uniform diameter throughout its entire length is slipped over the end of the shaft 1 and is secured in place on the shaft by 55 means of a set screw 4 carried by the hub

and adapted to engage a longitudinal slot or key-way 5 in the shaft. A stop pin 6 is fixed in the shaft 1 and limits the movement of the head 2 in one direction along the shaft. The head 2 differs from the conventional construction in that the bore thereof is uniform in diameter for its entire length while the bore of an ordinary head is tapered. The head 2 is releasably secured to the shaft in the manner described; 60 whereas the conventional head is secured to the shaft by caulking or in a like manner.

65 A head 7 which embodies the present invention is slipped over the end of the shaft 1 and is moved along the latter until 70 positioned at a desired distance from the head 2. As illustrated to advantage in the drawings, the head 7 comprises a body 8 having a peripheral flange 9 formed thereon adjacent to its outer end and having an 75 integral hub 10 extending from the inner end thereof. The outer end or face of the head 7 is recessed, as at 11, nearly to the hub 10 and the latter is provided with a bore 12 extending therethrough into communication with the recess 11. The bore 12 is of uniform diameter throughout its length and is of such diameter as to permit 80 slideable movement of the head along the shaft 1 without permitting undue play between these parts. A key-way 13 formed in the wall of the bore 12 is adapted to engage a spline 14 carried by the shaft 1, whereby the head 7 is held against rotation 85 relatively to the shaft 1 while being permitted to move longitudinally thereof.

90 The hub 10 is split from its outer end by slits 15—15 extending through its walls in a diametrical plane and terminating short of but adjacent to the juncture of the hub 95 10 with the body 8. It is to be observed at this point that the plane of the slits 15—15 extends substantially at right angles to the plane of the key-way 13.

99 A collar 16 is slidably mounted upon the hub 10 and is fashioned with diametrically opposed bosses 17 and 18 respectively. The collar 16 is arranged upon the slotted portion of the hub 10 so that the bosses 17 and 18 lie in a plane extending substantially 100 at right angles to the plane of the slits 15—15. The collar 16 is then secured to one portion of the split hub by means of a pin 19 projected through the boss 18 into engagement with the bore of the split hub. 105 110

A set screw 20 engaging a threaded bore 21 extending radially through the boss 17 is now tightened to occasion a pressure upon the other portion of the split hub, thereby 5 constricting the bore of the hub and clamping the portions of the split hub to the shaft.

A cylinder body 22 is then mounted upon the heads 2 and 7 and is secured thereon in any suitable known manner. The cylinder 10 22 differs from the conventional cylinder only in that it is provided with openings 23 and 24 through its walls, which openings are located respectively in position to afford access to the set screws 4 and 20 and to 15 permit of tools being inserted through the openings to effect the manipulation of the set screws, as desired.

From the foregoing description of the various parts of the device the operation there- 20 of may be readily understood.

In the event that the shaft 1 should be broken in service and the replacement there- 25 of is necessary, the set screws 4 and 20 are loosened and the broken shaft is withdrawn from the cylinder with the necessity of tearing down the cylinder or removing it from the spinning frame obviated. In the event that the shaft 1 should be broken at a point 30 between the heads 2 and 7, a suitable tool for gripping the shaft 1 may be inserted through the openings 23 and 24 and placed in engagement with the shaft intermediately of the heads 2 and 7, whereupon the broken 35 portions of the shaft may be worked free of the heads. Grooves 25 may be formed in the shaft at intervals between the pin 6 and the proximate end of the hub 10 to insure the engagement of a gripping tool with the shaft. In the event that the shaft has been 40 broken at a point between the heads 2 and 7, the broken end portion of the shaft cannot fall between the heads since it must of necessity be of greater length than the distance between the hubs 3 and 10 as the com- 45 bined length of the hub 3 and the portion of the shaft projecting beyond the end of the head 2 remote from the hub 10 is greater than the distance between the proximate ends of the hubs 3 and 10.

50 With a cylinder of ordinary construction, the breaking of a shaft and the consequent replacement thereof necessitated the removal of the cylinder from the spinning frame and the removal of the spinning bands and 55 associated parts from the cylinder as well as the disassembly of the cylinder and the removal of the outer head thereof from the cylinder body. This must be done preliminarily to the replacement of the shaft and 60 as a result considerable time was lost and the production of a spinning machine of which the cylinder was a part was curtailed appreciably on account of the necessity of replacement of a shaft. As will be understood 65 from the foregoing description, a cylinder

embodying our invention need not be removed from the spinning frame nor torn apart to permit of the replacement of a broken shaft and as a result the repairs necessitated by the breaking of a shaft can be 70 effected in considerably less time than has been possible heretofore, thereby effecting a saving of labor, time and production. Moreover, since the head embodying our invention is adjustably and detachably secured to the shaft it can be slidably moved back and forth on the shaft and positioned at different distances from the head 2 in order to compensate for deviations of a cylinder body from a specified length. Moreover, 75 since the hub of the head embodying our invention is split and can be constricted in the manner described, the hub may be longer than is ordinary and thus provide a bearing surface on the shaft which is of sufficient extent to stabilize the head 7 to a degree here- 80 tofore impossible of attainment.

Obviously, our invention is susceptible of embodiment in forms other than that which is illustrated in the accompanying drawings and we, therefore, consider as our own all modifications and adaptations or forms of the device disclosed herein which fairly fall within the scope of the appended 85 claims.

We claim:

1. A cylinder unit of the character de- 90 scribed comprising a shaft, two heads each having a hub extending laterally of one face thereof, said heads being adapted to be movably mounted on the shaft with the hubs in confronting relation, adjustable means 95 carried by each hub for releasably securing it to the shaft, and a cylinder body spanning the heads and having openings through its walls substantially in radial alignment with said adjustable hub securing means, said openings being adapted to permit of the insertion therethrough of a suitable tool for manipulating said adjustable securing 100 means.

2. A cylinder unit of the character de- 105 scribed comprising a shaft having a portion provided with a circumferential groove, two heads, each having a hub extending laterally of one face thereof, said heads being adapted to be movably mounted on the shaft at opposite sides of the grooved portion of the shaft and with the hubs in confronting 115 relation, adjustable means for releasably securing the hubs to the shaft, and a cylinder body spanning the heads and having an opening through its walls to permit of the insertion of a suitable tool or tools for manipulating said hub securing means and for 120 engaging with the grooved portion of the shaft to move the latter axially when released from the hubs.

WINGO HERRON.
JOSEPH H. JESTER.
